UNITED STATES PATENT OFFICE.

FRANK B. COMINS, OF NEWTON, MASSACHUSETTS.

HUMIDIFIER.

1,139,640.

Specification of Letters Patent.

Patented May 18, 1915.

Application filed March 10, 1913. Serial No. 753,156.

To all whom it may concern:

Be it known that I, FRANK B. COMINS, of Newton, county of Middlesex, formerly of Sharon, county of Norfolk, State of Massachusetts, have invented certain new and useful Improvements in Humidifiers, of which the following is a specification, reference being had to the accompanying drawings, forming part thereof.

10 This invention has reference to improvements in humidifiers and particularly to such devices specially adapted for the supplying of moisture to warps of looms.

15 The object of this invention is to so construct a humidifier of this nature that it may be applied to a loom without obstructing access to the loom in any manner and whereby moisture may be supplied to the warp threads during their operation in the loom 20 and preferably to those portions of said warp threads extending between the warp beam and the lay.

25 Another object of the invention is to provide a simple and efficient humidifier adapted to receive moistened air from beneath the floor of the weave room and to deliver said moistened air above said floor within the boundary of the loom frame.

30 Other objects of the invention will appear from the following description.

The invention consists in the novel construction of the improved humidifier.

35 The invention also consists in such other novel features of construction and combination of parts as shall hereinafter be more fully described and pointed out in the claim.

40 Figure 1, represents a side elevation of the improved humidifier partially broken away and shown in section illustrating the invention as applied to a loom. Fig. 2, represents a plan view of the delivery or mouth piece of the humidifier in relative position to a loom which latter is indicated.

45 Similar reference characters designate corresponding parts throughout.

As shown in the accompanying drawings A represents the floor of a weave room and B the frame of a loom of any well known construction of which C is the warp beam and D the lay.

50 The improved humidifier comprises the chamber 5 which forms a communication and drip receptacle between the two cylinders or air conduits 6 and 7 which approximately are parallel. Cylinder 6 is shorter than that marked 7 whereby the open upper

end of this cylinder 6 is spaced from the floor A, and in the open upper end of this cylinder 6 is located the spray head or atomizer 8 of any well known construction to which water under pressure may be supplied. Cylinder 7 is secured to the floor A and extends through a suitable opening in said floor at a point within the boundary of the loom frame and preferably between those portions which respectively sustain the warp roll C and the lay D. The upper end of cylinder 7 is furnished with the mouth piece 9 having the dished bottom member 10, whereby moisture thereon may drain back into said cylinder 7 while the top of said mouth piece is formed by the deflector 11 mounted on said members and having the depending drip member 12 positioned above said cylinder 7 so that moisture accumulating on said deflector 11 may drain into said cylinder 7.

55 In the operation of this improved humidifier water under suitable pressure is supplied to the spray head or atomizer 8 and is delivered thereby as spray to cylinder 6. As a result of such spray a current of air is induced to flow into the open end of cylinder 6 and such air becomes moistened or humidified and then passes through chamber 5 into cylinder 7 from whence said moistened air is delivered or circulated through the openings between the edges of the mouth piece member 10 and the deflector 11. Said moistened air then rises toward the warp extended between the warp roll C and the lay D and supplies moisture to said warp without the danger of undue moistening such warp as is present in moistening devices which deliver moisture above the warp. In the operation of this device, if there be any accumulation of moisture sufficient to form drops, the specific gravity thereof will carry said drops downward or at least the comparatively light current of air induced to flow through this humidifier will not have sufficient velocity to carry upward to the warp atoms of moisture of sufficient size to injure said warp.

60 The surplus of moisture delivered by the spray head 8 is drained from chamber 5 in any usual manner and the surplus moisture carried forward by the air beyond said chamber 5 accumulates on the walls of cylinder 7, or of the mouth piece 9 and drains backward ultimately into the chamber 5.

65 Having thus described my invention I

claim as new and desire to secure by Letters Patent.

In a humidifier the combination with a floor having an opening, of an air distributor comprising a pipe fixed to said floor and extending through said opening, a mouth piece slidably engaged with the upper end of said pipe and having lateral outlets and a drip member, a chamber attached to the

lower end of said pipe, and a second pipe 10 mounted on said chamber and extending toward said floor but spaced therefrom to permit entrance of air to said second pipe.

FRANK B. COMINS.
